UNITED STATES PATENT OFFICE.

ALFRED L. NEILAN, OF SAGINAW, MICHIGAN.

CONNECTING DEVICE FOR WATER-TANK-VALVE LEVERS.

1,074,734.

Specification of Letters Patent.

Patented Oct. 7, 1913.

Application filed April 24, 1912. Serial No. 692,530.

To all whom it may concern:

Be it known that I, ALFRED L. NEILAN, residing at Saginaw, in the county of Saginaw and State of Michigan, have invented a Connecting Device for Water-Tank-Valve Levers, of which the following is a specification.

In water tanks of large capacity, particularly those used over railroads for filling the water reservoirs for locomotive engines, the valve lever is directly connected to the rod that passes up to and directly connects to one arm of the quadrant or bell crank lever in the top of the tank which has a flexible connection at the side of the tank having the hinged delivery spout for conveying the water that flows from the bottom of the tank to the engine tender.

From practical observation, I have discovered that the present method of connecting the controlling valve for the tank outlet, there is always an excess pressure on the valve when closed, of an extent at least that of the weight of the connecting rod that joins the valve and the quadrant lever at the top of the tank, which excess pressure tends to wear the valve and unnecessarily reduces its efficiency and length of use. Again, in the use of the present type of connections between the valve lever and the quadrant lever there are always present conditions that tend to cause the valve to improperly engage its seat and thereby cause a consequent leakage from the tank.

My invention seeks to overcome the objections above noted in the use of the water delivering controls for tanks and to provide a simple, inexpensive and easily applied device for connecting the operating rod with the tank lever and in such a manner that a considerable saving on the maintenance of tank valve is effected, and to such ends my invention consists in the peculiar arrangement and coöoperative connection of the parts hereinafter fully described, specifically pointed out in the appended claim, and illustrated in the accompanying drawings, in which:

Figure 1, is a vertical section, parts being in side elevation, of a water tank with my improved valve connection device applied. Fig. 2, is a perspective view, parts being in section of the valve device and the lower end of the connecting device that coöperates with the valve lever, the said device being shown as pulled up for holding the valve

open. Fig. 3, is a detail side elevation of the connecting device and the valve lever, the parts being at their normal position. Fig. 4, is an end elevation thereof. Fig. 5, is a plan view of the same, parts being in horizontal section.

In the drawing, 1 designates the tank, 2 the valve seat, that is coupled to the ejecting pipe 3 that extends under the tank and discharges into the delivery spout 4 hinged to the side of the tank.

5 designates the hinged drop valve that coöperates with the seat 2, and has the usual long lever member 50. 6 designates the quadrant or bell crank lever in the top of the tank, 7 the flexible member that extends through the top of the tank and hangs adjacent the spout 4, and 8 designates the counterpoise connection that joins with the spout 4 and the tank, all of the above being of the well known construction now in common use on railroads.

My invention is embodied in the means for connecting the bell crank lever 6 with the valve lever 50, and the same consists of the hanger rod 10 whose lower end terminates in an elongated slotted yoke 11 that straddles the valve lever 50.

In practice, the length of the rod 10 is such that when the valve 5 is closed, and under normal conditions, the lever 50 projects through the yoke 11 midway its length, so as to be entirely free from connection with the rod yoke 11. The object in thus arranging the lever 50 and the rod 10 is, that under normal conditions all weight (other than that of the valve lever itself) on the valve 5, is overcome and since the rod 10 is readily adjustable by a turnbuckle 95 so that it will hang suspended from the lever 6 at the top free from connection with the lever, it thereby eliminates any pressure whatever on the tank valve 5.

For guiding the rod 10 and to hold it to its true position relatively to the lever 50, and further for eliminating the danger of the parts frictionally gripping during the operation of lifting the lever and when valve freely returns to its normal position, I have provided guide devices mounted in the lever as shown. The guide devices consist of a pair of link plates 12—12 joined by cross bolts 13 that pass through the lever 50 and receive the nuts 14—14. Spacing sleeves 15 are mounted on the bolts 13 at each side of the lever that act as friction

rollers, for engaging the opposite edges of the yoke end of the suspended rod 10, as it tends to swing laterally on the lever 50.

By reason of my improved device, when the tank spout is swung down in the usual manner, and the lever 6 at the top is rocked in the direction indicated by the arrow α , the lower end of the yoke 11, in rising, strikes the lever 50, lifts and holds it up when the spout is down, said lever and the rod 10 being returned to their dropped position when the spout has been raised up. By providing a loose suspension of the rod 10, and a limited free riding of the yoke 11 end thereof on the lever, it is obvious that any slight contraction of the rod 10, particularly in very cold weather, would have no effect whatsoever on the valve 5 and hence danger of a slight lift of the valve and

unnecessary leakage of the water from the 20 tank is overcome.

What I claim:

In a valve control for water delivery means of the character stated, and in which is included a hinged drop valve having a 25 lever member, a lifting connection for the said member that comprises a slotted yoke through which the lever member extends and in which it has free movement, and means on the lever member for holding the yoke 30 and the said member from separation, the said means including studs on the lever having roller bearings between which the yoke end of the lifting rod plays.

ALFRED L. NEILAN.
